[57] CLAIM

The ornamental design for an eyeglass sun visor, as shown and described.

DESCRIPTION

FIG. 1 is a top plan view of an eyeglass sun visor showing our new design;

FIG. 2 is a front elevational view thereof;

FIG. 3 is a right side elevational view thereof, of which the left side elevational view is a mirror image;

FIG. 4 is a bottom plan view thereof; and

FIG. 5 is a rear elevational view thereof.

FIG. 1

FIG. 3

FIG. 2

FIG. 4

FIG. 5
